US0D1026587S

(12) **United States Design Patent** (10) Patent No.: **US D1,026,587 S**
(45) Date of Patent: ** May 14, 2024

(54) **CAN OPENER**

(71) Applicant: **Helen of Troy Limited**, St. Michael (BB)

(72) Inventors: **James Kwon**, Williston Park, NY (US); **Kristopher Wagner**, Brooklyn, NY (US)

(73) Assignee: **Helen of Troy Limited**, St. Michael (BB)

(**) Term: **15 Years**

(21) Appl. No.: **29/831,251**

(22) Filed: **Mar. 18, 2022**

(51) LOC (14) Cl. **07-99**

(52) U.S. Cl.

USPC **D8/40**

(57) **CLAIM**

The ornamental design for a can opener, as shown and described.

DESCRIPTION

FIG. 1 is a perspective view of a can opener showing our new design;

FIG. 2 is a perspective view of FIG. 1;

FIG. 3 is a front elevation view of FIG. 1;

FIG. 4 is a rear elevation view of FIG. 1;

FIG. 5 is a left side elevation view of FIG. 1;

FIG. 6 is a right side elevation view of FIG. 1;

FIG. 7 is a top plan view of FIG. 1; and,

FIG. 8 is a bottom plan view of FIG. 1.

The broken lines in the drawings depict portions of the can opener that form no part of the claimed design.

1 Claim, 6 Drawing Sheets
